Fig. 6.

Fig. 7.

FIGURE 1 is a perspective view of a body for a file frame or the like, showing my new design;

FIGURE 2 is a side elevational view thereof, with the opposite side not shown being of similar appearance;

FIGURE 3 is a fragmentary side elevational view thereof, showing the right of the two movable knobs (in broken lines for illustrative purposes only) in an alternative position;

FIGURE 4 is a top plan view thereof with the knobs omitted for ease of illustration;

FIGURE 5 is a bottom plan view thereof, with the knobs omitted for ease of illustration;

FIGURE 6 is an end view thereof on a slightly larger scale, taken from the right hand end of FIGURE 2; and

FIGURE 7 is an end view thereof, also on a slightly larger scale, taken from the opposite or left hand end of FIGURE 2.

The broken line showing of hand knobs in conventional relationship is for illustrative purposes only.

I claim:

The ornamental design for a body for file frame or the like, substantially as shown and described.
